Primary Examiner — Mitchell I. Siegel(74) Attorney, Agent, or Firm — Klarquist Sparkman LLP(57) CLAIM

I claim the ornamental design for a golf club, as shown and described.

DESCRIPTION

FIG. 1 is a perspective view of a golf club, as viewed from the front, above and one side.

FIG. 2 is a front elevation view of the golf club of FIG. 1. FIG. 3 is a rear elevation view of the golf club of FIG. 1. FIG. 4 is a side elevation view of the toe of the golf club of FIG. 1.

FIG. 5 is a side elevation view of the heel of the golf club of FIG. 1.

FIG. 6 is a top plan view of the golf club of FIG. 1. FIG. 7 is a bottom plan view of the golf club of FIG. 1; and, FIG. 8 is a perspective view of the golf club of FIG. 1, as viewed from the rear, below and one side.

The broken line showing is included for the purpose of illustrating unclaimed subject matter and forms no part of the claimed design. The dash-dot-dash lines are included as boundary lines and form no part of the claimed design. The drawings are lined for the colors silver and black. The lining on at least part of the top surface of the club head is intended to represent the color silver. The lining on at least part of the club face represents the color black.
